UNITED STATES PATENT OFFICE.

CHARLES LOUIS MEYER, OF OMAHA, NEBRASKA.

REMOVABLE MOLD FOR CONCRETE FLOORS.

1,106,665.

Specification of Letters Patent. Patented Aug. 11, 1914.

Application filed July 31, 1912. Serial No. 712,455.

To all whom it may concern:

Be it known that I, CHARLES LOUIS MEYER, a citizen of the United States, residing at Omaha, in the county of Douglas and State of Nebraska, have invented certain new and useful Improvements in Removable Molds for Concrete Floors, of which the following is a specification.

This invention relates to a removable mold for use in the construction of reinforced, concrete floors of buildings, and has for its object, broadly, to provide a novel means by use of which these floors may be conveniently formed, and at less than ordinary expense.

The invention has reference to a separable two part mold, each part being formed of a metallic sheet bent to provide a substantially rectangular top, and upright sides with outwardly projecting, perforated, terminal flanges, one of the parts being provided with a closed end, said parts being convenient for disposal end-to-end in connected relation to provide forming-sections having closed ends, the sections being disposed side-by-side for the purpose of forming, in connection with the usual supply of concrete and metallic reinforcing material, a complete concrete floor.

The invention also includes means to prevent "skidding" or longitudinal movement of the parts of the mold with reference to each other, and means to prevent spreading or collapsing or a lateral movement of their upright walls, and discloses a construction by use of which the parts of the mold may be readily removed from the concrete, after the floor has been completed.

The invention consists of the novel construction, combination and arrangement of parts as described herein and claimed, and as illustrated in the accompanying drawing, wherein—

Figures 1 and 2 are, respectively, side and plan views of the device. Fig. 3 is a broken view showing the parts of the device arranged end-to-end to provide a forming-section, a part of a concrete floor being added and in section. Fig. 4 is a transverse sectional view, partly broken, illustrating the use of the device to provide the forming-sections for the reinforced concrete beams and floor. Fig. 5 is a view similar to that shown in Fig. 4, the molds being removed, and the usual steel lath sheets and plaster

being added. Fig. 6 is a broken, plan view, on a reduced scale, showing the device arranged end-to-end between two horizontal supporting-beams of a building, to provide a complete forming-section. 60

Referring now to the drawing for a more particular description, the mold shown best in Figs. 1 and 2, consists of parts or portions 7 and 8, and these parts may be used to provide a forming-section 9, shown in Fig. 6. Parts 7 and 8 are formed of metal, and each is provided with a substantially rectangular top *a*, upright sides *b* with transverse outwardly-projecting flanges *c* and, preferably, they are suitably curved as indicated at *d*, these curved portions occurring at the junction of the top and sides and at the junction of the sides and flanges; and part 8 is provided with an end portion *e* which covers the area between its top and sides. While the two parts 7 and 8 are shown and may be used as a complete mold, it will be understood that they are separable, and a plurality of these molds may be employed to provide a support or forming-section 9 upon which may be laid the concrete for the floor 10 and beams 11 of a building. 75 80

In practice, to form a reinforced concrete floor, the parts 7 and 8 are disposed end-to-end between the main, parallel supporting-beams 12 of a building, the end of one part overlapping the end of the other to provide a forming-section 9. The forming-sections will be disposed side-by-side, the flanges *c* which appear in one section overlapping the flanges *c* of an adjacent section to form therebetween parallel channels 13 (Fig. 6) for the formation of floor beams 11, a space being also formed between the ends *e* and 95 the main supporting beams 12 which may be filled with concrete to form a cross-tie or connection 14 (Fig. 3) between said floor beams 11. For sustaining the parts 7 and 8 to form the floor and beams 11 as described, any suitable planks 15 and posts 16 or like supports may be employed, care being exercised so that the flanges *c* of one forming-section will overlap the flanges *c* of an adjacent forming-section, and that the lower part of ends *e* will be disposed near to or make contact with the lower part of supporting-beams 12. It will be seen that the molds when arranged as described, provide endless troughs or channels in which 100 105 110

the required concrete material and usual metallic reinforcing bars or rods 17 may be laid.

At *f* (Fig. 2) are indicated perforations 5 formed at longitudinal intervals in flanges *c*.

At 18 are indicated suitable wire strands supported by the rods 17 and which traverse the perforations; and after the molds have been removed, the sheets of steel lath 19 may 10 be secured to the wire in a well known manner.

The plaster upon the lath is indicated at 20.

The two parts 7 and 8 may have any suitable length or width, and may be employed 15 as illustrated in Fig. 6 where parts 8 are disposed at the ends of the forming-sections, and a plurality of parts 7 are disposed therebetween. The mold may be constructed to 20 advantage of sheet metal bent to the forms described, and to prevent spreading or lateral movements of the sides *b*, adjusting- rods 21, of uniform length are employed. They are provided with terminal hooks *g* 25 adapted to catch into ears or loops 22 formed in sides *b*. Loops 22 may be conveniently provided by forming parallel incisions *i* (Fig. 1) in sides *b* adjacent to flanges *c*, and bending the material inwardly between 30 said incisions, and as is obvious, other or different holders or loops may be provided. Any desired number of adjusting-rods may be employed, and as is apparent, the adjusting-rods when thus mounted will operate 35 to prevent spreading and will also prevent sides *b* from moving toward each other when the concrete is laid in channels 13. After the concrete floor and beams have been completed, the several parts 7 and 8 40 may be removed from the surface of the concrete. To effect their removal, the adjusting-rods are disconnected from the loops after the wood blocking or supports 15 and 16 have been taken away, and the loops 45 vide inwardly projecting holders for engagement with any suitable hooked implement (not shown) for dislodging or separating said members 7 and 8 from the concrete.

The two-part implement thus described 50 may be said to be of substantially inverted

U-shape in cross-section, and it may be economically manufactured on account of its simple construction. Since it is made of metallic sheets it is of comparatively light weight, and may be conveniently transported or mounted in the positions described, and the material being elastic, may be more readily removed from the concrete after the floor has been completed. The oppositely-disposed sides *b* of each member and end-portion *e* of member 8 may be formed flaring or downwardly divergent from the tops *a*, as shown in the drawing, and this construction facilitates the removal of said members 7 and 8 from the floor and floor 65 beams.

In order to prevent "telescoping" or sliding movements of members 7 and 8 which might be occasioned by stresses directed longitudinally thereof when laying the concrete to form the connections 14, any suitable coöperating devices may be provided, the means herein shown for this purpose being the upwardly-projecting lugs 23 formed in flanges *c* of one member or part and 70 adapted to bear upon the ends of the flanges of the adjacent member or part.

Having fully described my invention, what I claim and desire to secure by Letters Patent is,—

A mold for concrete floors comprising a body portion of inverted U shape in cross section, having horizontal outturned flanges extending longitudinally along the lower edges of its side walls, there being openings 85 formed vertically through said flanges said openings being nearer to the side walls than to the outer edges of the flanges, whereby when a plurality of said molds are arranged side by side to construct a floor with their flanges partially overlapping each other said openings may lie outside of said overlapping portion to permit the passage of lath retaining strands through said openings.

In testimony whereof I have affixed my 95 signature in presence of two witnesses.

CHARLES LOUIS MEYER.
